UNITED STATES PATENT OFFICE

CECIL J. DAVIS, OF KENTON, OHIO, ASSIGNOR TO THE OHIO MACHINE TOOL COMPANY,
OF KENTON, OHIO, A CORPORATION OF OHIO

SHAPER

Application filed March 5, 1928. Serial No. 259,349.

This invention relates to improvements in metal shapers, such as are used in railway shops, where it is desired to machine locomotive driving boxes or other devices.

The object of the invention is to provide an improved shaper including a reciprocating body or ram carrying a toolhead and shaping tool at its forward end, together with means for laterally adjusting the tool on the head to vary the depth of cut, the tool adjusting means being entirely located within the confines of the ram and tool-head and avoiding lateral projection therefrom, so that the ram may be reciprocated through a confining opening, and in which the tool adjusting mechanism is operable manually from the front of the head, in connection with which a micrometer scale is provided, enabling the operator to manually produce a fine adjustment of the mechanism while the machine is operating, all for purposes which will more fully appear hereinafter.

Further objects of the invention are in part obvious and in part will appear more in detail hereinafter.

In the drawings, which represent one suitable embodiment of the invention, Fig. 1 is a side elevation, illustrating the ram applied in use; Fig. 2 is an end elevation from the left in Fig. 1; Fig. 3 is a longitudinal sectional elevation on a larger scale on the line 3—3, Fig. 2; Fig. 4 is a sectional plane view on the line 4—4, Fig. 3; Fig. 5 is an end view, partly in section on the line 5—5, Fig. 6; and Fig. 6 is a side elevation, partly broken out and in longitudinal section on the line 6—6, Fig. 5.

The general features of the present ram are of ordinary form and require neither illustration nor full description. Briefly, the machine includes the usual frame 1 provided with ways 2 in which is horizontally slideable the ram 3, usually actuated by an oscillating arm (not shown) in the frame. On the ways 2 is longitudinally adjustable a dog 4 having inclined cam faces 5 and 6 and adapted to be secured in various positions along the ways to actuate the tool feeding mechanism, as will appear.

The work to be machined, marked 8, is

mounted upon the frame bed 7 and in the drawings is shown as a locomotive driving box in which a cylindrical opening is to be machined. The opening is slightly larger than the body of the ram and the clearance is insufficient for the lateral projections formed by the common tool adjusting devices, which usually project laterally outwardly from the ram and, therefore, extend beyond the confines of its body, thereby limiting possible uses of the machine and also making it difficult for the workman to adjust the parts.

In the present construction the ram body is provided internally with bearings, 9, 10 for a central longitudinal shaft 11 provided at its front end with a cylindrical head 12 and at its rear end with means for rotating it, such as the worm wheel 13. The forward or head end of the shaft will first be described.

On the head 12 is mounted a tool-carrier 14, pivoted to swing about a horizontal pin 15 and normally held in the position shown in Fig. 3 by the compression spring 16 surrounding screw 17. This arrangement automatically permits the tool-carrier to relieve the tool from the work on the backward or return stroke, as is usual.

On the tool-carrier 14, or in other words, on the oscillating or swinging part, is mounted the cutting tool 18, together with the necessary parts for accomplishing its adjustment. As indicated, the tool 18 is held in a slot in a tool box or holder 19 mounted to slide vertically in an under-cut way or channel 20 of the tool-carrier. The walls of the box on opposite sides of the tool are connected at their upper end by a cross-pin 21 which forms a backing stop for the upper end of the tool and limits its upper position in the tool box. The rear of the box is threaded at 22, so that it forms a nut co-operating with a threaded shaft 23 swivelled in the carrier at 24 and provided with a bevelled gear 25 meshing with a bevelled gear 26 on a shaft 27 provided at its outer end with a hand knob 28 for rotating it. By rotating said knob the tool box and the tool carried thereby may be adjusted up and down, in Fig. 3, to vary the distance of the cutting edge from the central axis of shaft 11. The tool is held in the tool

box by a plate 29 clamped to the box by a series, four being shown, of clamp screws 30, and the tool box may be rigidly and immovably clamped to the carrier by a clamping bar 31 extending across the plate 29 and 5 clamped against the same by nuts 32 threaded on bolts 33 fixed in the carrier.

All parts of the mechanism, it will be noted, are within the confines or outer peripheral boundaries of that portion of the ram body 10 which enters and recedes from the work, as shown in Fig. 3, except that the tool and possibly a part of the tool box may extend beyond it as the tool is adjusted outwardly. The clearance between the ram and the surface of the finished opening, therefore, may be a minimum. Moreover, the knob 28 is at the extreme front end of the ram, readily accessible to a workman standing at the front 15 of the machine. Each time the free forwardly projecting end portion of the ram advances to conveniently accessible or exposed position the knob 28 may be given a slight turn until the tool is finally adjusted to exactly the proper position for the finished cut, because 20 obviously the pitch of the screw threads 23 and the ratio of the gearing 25, 26, may be made as fine as desirable.

The shaper may also be provided with convenient vernier indicating means, such as a 30 collar 34 rotatable on the shaft 27 but capable of being fixed in any angular position thereon, such as by a set screw 35, and provided with a vernier scale 36 co-operating 35 with indicating marks 37. This vernier scale is closely adjacent to the knob 28 and within the immediate vision of the operator. In use of the machine the tool 18 is set at some 40 basic position, such as with reference to an indicating mark on the machine frame or by accurate measurement from the surface of the bed 7, and when in that basic position is clamped in the tool box by the plate 29. The vernier collar 34 is then adjusted to zero 45 and manipulation of the knob 28 will produce accurately measured adjustment of the tool to any desired depth of cut. Usually the workman makes the zero adjustment, 50 clamps the tool in the box 19, starts the machine and makes fine manual adjustments of the tool until the desired depth of cut is reached and then clamps the heavy clamping bar 31 to fix the tool in position, whereupon he throws in the rotating feeding mechanism 55 and produces step-by-step feed of the tool in the arc of a circle for the working operation.

To feed the tool laterally along the work means is provided for rotating shaft 11. As 60 shown the worm gear 13 at the rear end of said shaft is driven by a worm 38 on a lateral shaft 39 provided at its outer end with a hand wheel 40. Said shaft also carries a ratchet wheel 41 with which co-operates a releasable spring pawl 42 mounted in a sleeve 43 65 rotatable on the shaft and yieldingly urged

in one direction by a spring 44. Said sleeve is provided with an arm 45 having a roller 46 adapted to travel on the cam surfaces of the dog 4 as the ram approaches its rear position. In the sleeve 43 is a spring pressed 70 pin 50.

Each time the ram makes its receding stroke the roller 46 rides up on the cam surface 5. If the spring dog 42 is let in so that it is effective the rotating motion of the sleeve turns shaft 39 and also the shaft 11 and feeds the tool angularly one step. The sleeve 43 is returned to initial position by spring 44. If, by chance, the dog 4 is set at the wrong position—advanced too far—roller 46 will travel 75 beyond the cam 5 and up over cam 6, to an extreme or safety position, in which the spring plunger 50 enters an opening 47 and holds the sleeve 43 against return, so that further feed is prevented.

At one side of the worm wheel 13 the shaft 11 is provided with a drum portion surrounded by a split collar 48, the ends of which are forced together by a clamp screw 49. By screwing up this screw the shaft 11 may be 80 clamped against rotation in case it is desired to use the ram without lateral feed of the tool.

The advantages of the invention are these: The operator stands at the front of the machine or, in other words, at the left in Fig. 1, 95 in a position where the ram approaches him on each of its cutting strokes. He therefore is in the best position to view the work. The operating knob 28 for the tool adjusting device is at the extreme front of the ram and is therefore very convenient for manipulation because the operator has no difficulty in finding it with his hand, nor does he need to reach in to the machine beyond other parts to grasp it with possible liability of injury. He can make the tool adjustment without moving from his position at the front of the machine, and, moreover, is enabled to make the tool adjustment while the machine is actually working. Each time the ram comes forward and the tool passes through the work, the operator can grasp the knob 28 and make such adjustment as may be necessary.

Frequently the work involves one or more cuts at different depths and the adjustment for a new depth or to secure the proper depth of cut may be made while the machine is running. Of course, when the final finishing cut is made, for greater rigidity the operator, if he desires, may stop the machine and clamp the tool in place by means of the clamping bar 31. In all cases very minute adjustments may be made even when the machine is running, by the use of the micrometer dial. As a result, this machine is convenient and safe 125 to operate and will produce very accurate work in the least possible time, due to the lack of necessity for stopping the machine every time a tool adjustment is made.

What I claim is:

A shaper for cutting cylindrical surfaces, comprising a reciprocating ram body having a free advance end portion adapted to enter and recede from the work, a tool head mounted at the advance end of said body to rotate about a longitudinal axis, a tool carrier mounted on said head to swing fore and aft about a transverse axis to relieve the tool on the receding stroke, a tool holder slideable laterally on said carrier, and operating mechanism therefor, comprising feed screw mechanism rotatable about a transverse axis and connecting said carrier and holder for laterally adjusting the latter, and an operating 10 shaft connected to said mechanism and rotatable in the carrier and having a forwardly extending portion readily accessible and operable manually while the ram body is moving in advanced position, said head, carrier, 15 holder and operating mechanism being wholly contained within the outer boundary of the ram body for reciprocation through a confined opening.

In testimony whereof I hereby affix my signature.

CECIL J. DAVIS.
